CLAIM

The ornamental design for a warehouse robot as shown and described.

DESCRIPTION

FIG. 1 is a front view of a warehouse robot;

FIG. 2 is a rear view thereof;

FIG. 3 is a left view thereof;

FIG. 4 is a right view thereof;

FIG. 5 is a top view thereof;

FIG. 6 is a first perspective view thereof; and

FIG. 7 is a second perspective view thereof;

FIG. 8 is a detail view of the encircled portions on FIG. 1;

FIG. 9 is a detail view of the encircled portions on FIG. 2;

FIG. 10 is detail views of the encircled portions on FIG. 3;

FIG. 11 is detail views of the encircled portions on FIG. 3;

FIG. 12 is detail views of the encircled portions on FIG. 4;

FIG. 13 is detail views of the encircled portions on FIG. 4;

FIG. 14 is a detail view of the encircled portions on FIG. 5;

FIG. 15 is detail views of the encircled portions on FIG. 6;

FIG. 16 is detail views of the encircled portions on FIG. 6;

FIG. 17 is detail views of the encircled portions on FIG. 7; and,

FIG. 18 is detail views of the encircled portions on FIG. 7.

The broken lines in the figures illustrate portions of the warehouse robot that form no part of the claimed design. The dash-dot broken lines that encircle portions of FIGS. 1-7 and that border the FIGS. 8-18 detail views indicate outer limits of enlarged areas of the figures and form no part of the claimed design.

1 Claim, 18 Drawing Sheets
